UNITED STATES PATENT OFFICE

2,151,916

BOMB

Jan Pierre Hulswit, Noroton, Conn.

Application December 17, 1937, Serial No. 180,281

13 Claims.

(Cl. 102—2)

My invention relates to aerial bombs and more particularly to improvements in the type of bombs disclosed in my U. S. Patent No. 2,087,287 granted July 20, 1937.

5 In the above mentioned patent there is disclosed and broadly claimed a bomb device which is adapted to be dropped from an aircraft flying over water. The device includes a plurality of bombs secured to a carrier and arranged so that 10 if a direct hit on the target is not scored and the device falls into the water, the bombs are released therefrom and propelled by self-contained power plants in a plurality of directions radiating from the point of impact so the bombs 15 travel through the water and one or more of them may strike the target. The objects and advantages of my present invention will be apparent from the following description considered in connection with the accompanying drawings 20 which form a part of this specification and of which:

Fig. 1 is a side view, partially broken away, of a bomb device in accordance with my invention;

Fig. 2 is a top view of the device shown in Fig. 1;

25 Fig. 3 is a cross-sectional view taken on the line 3—3 of Fig. 1;

Fig. 4 is a cross-sectional view taken on the line 4—4 of Fig. 2;

30 Fig. 5 is a view on an enlarged scale of a portion of the device shown in the preceding figures;

Fig. 6 is a view similar to Fig. 5 but with certain parts in different relative positions;

Fig. 7 is a cross-sectional view taken on the line 7—7 of Fig. 1;

35 Fig. 8 is a cross-sectional view taken on the line 8—8 of Fig. 1;

Fig. 9 is a cross sectional view taken on the line 9—9 of Fig. 4;

40 Fig. 10 is a view on an enlarged scale showing a detail; and

Fig. 11 is a cross-sectional view taken on the line 11—11 of Fig. 10.

Referring more particularly to Figs. 1 through 4, reference character 10 designates generally a carrier which includes a central shaft 11 having an enlarged upper end 12. A plurality of vanes or rudders 13 radiate from the enlarged end 12 and serve to maintain the device in a substantially vertical position during descent. The rudders 13 are provided with lugs 14 on either side thereof and pins 15 extend between adjacent lugs. Bomb cradles 16 are provided with pairs of arms 17 which are pivotally secured to pins 15. Each 50 bomb cradle is provided with a bracket 18 which is adapted to be engaged by a latch member 19 mounted on a sleeve 20 which is rotatably supported on shaft 11. As shown, sleeve 20 and shaft 11 are formed with engaging threads 21 which 55 permit relative rotation to take place between the

two members while at the same time imposing a certain frictional restriction to such rotation. Sleeve 20 is formed with a plurality of spiral vanes 22 on its outer side.

5 A bomb or aerial torpedo 25 is releasably secured to each of the bomb cradles 16 and to the carrier 10. As appears clearly in Figs. 1 and 4, the bombs 25 are held with their longitudinal axes parallel to each other and to shaft 11. This results in a unit as compact as possible and which 10 may be stored advantageously aboard the aircraft. A further advantage of having the lateral dimensions of the unit as small as possible is that it increases armor piercing ability, should 15 a direct hit be scored. It also decreases the 15 resistance to passage through the air and reduces the probability of the devices being turned from a vertical position by air currents during its descent.

20 Each bomb is provided with a rudder 26 formed with an open ended slot 27. When the bombs are in place the pin 15 extends through slot 27 and is positioned in the closed end of the slot. Vanes 28 are pivoted on either side of rudders 26 by means of a pin 29. The location of pin 29 25 with respect to slot 27 is such that, when the vanes 28 are in a horizontal position, they contact the upper side of pin 15. Pins 30 are secured to lugs 14 and extend to adjacent opposite sides of the rudders 26 on the bombs. The location of 30 these pins is such that, when vanes 28 are in the aforementioned position, the pins 30 contact the upper surface of the vanes, thus preventing rotation of the vanes so as to release the pin 15. Consequently, as long as the bomb remains in a 35 vertical position with respect to the carrier 10 it is pivotally supported on the pin 15. The bomb cradles 16 are provided near their lower ends with spring-pressed detents 31, shown more particularly in Fig. 7, which engage slots 32 formed in 40 the exterior surface of the bombs and serve to prevent pivotal movement of the bombs with respect to the bomb cradles about the pin 15. Inasmuch as the brackets 18 and members 19, when 45 in engagement, prevent pivotal movement of the cradles, both the bombs and the cradles are held stationary with respect to the carrier.

50 The lower ends of the bombs are provided with vanes 33 which are inclined in a manner shown particularly in Figs. 1 and 6. The lower end of each bomb is also provided with a detonator head 36, the purpose of which is to explode the bomb upon impact with an object. Slidably secured to the lower end of shaft 11 is a protector member 37 which includes a hub portion 38 and arms 55 39. The protector member 37 is retained on the shaft 11 by means of a transverse pin 40 which extends through a slot 41. Pin 40 also serves to prevent rotation of member 37 with respect to the shaft. The arms 39 are arranged so as to be 60

disposed directly beneath the detonator heads 36 on each of the bombs, to thereby protect the heads from impact with the water. The arms 38 are streamlined so as to permit them to pass through water with a minimum impact. A spring 42 is disposed within sleeve 20 and between hub member 38 and an interior shoulder formed on the sleeve. The strength of spring 43 is so selected that it will hold the member 37 out of contact with detonator heads 36 upon the impact of the device with water, but will permit the member 37 to strike the heads 36 if the device falls on a solid object, to thereby explode the bombs. Spring 42 also serves to increase the frictional resistance to turning of the threads 21 to thereby prevent accidental rotation of the sleeve 20.

Each of the bombs 25 is provided with a self-contained power plant of any desired design which is connected to rotate a propeller 45 located at the stern of the bomb. Initiation of the operation of the power plant is caused by moving a lever 46 pivotally connected to rudder 26 of the bomb. Lever 46 is preferably U-shaped as shown in Fig. 11, the bottom part of the U extending through an arcuate slot formed in the rudder. A wire 48 is secured to lever 46 and extends to the interior of the bomb where it is connected to suitable mechanism for initiating operation of the power plant when the lever is pivoted so as to pull the rod or wire. As shown more particularly in Fig. 10, lever 46 is moved by coming into contact with the end of vanes 28 when the bomb is pivoted, in a manner which will be described in connection with the operation of the device.

The device operates as follows: When the device is released from an aircraft it falls as a unit, the bombs 25 and the cradles 16 being securely held in place in the position shown for instance in Fig. 1. The rudders 13 on the carrier and the rudders 26 on the bombs both serve to retain the unit in a vertical position during descent. As previously stated, latch members 18 engage brackets 18 on the bomb cradles and prevent the latter from pivoting about pin 15. The lower ends of the bombs and cradles are held together by means of the spring-pressed detents 31 and the upper ends of the bombs are secured to the carriage by means of pins 15 held within the slots 27 in the rudders 26 of the bombs. If the device strikes the water, arms 38 pass therethrough with sufficiently small resistance so that the spring 42 holds the arms away from the detonator heads 36 and the arms protect the heads from direct contact with the water, thereby preventing explosion of the bombs. As the device passes downwardly through the water, the relative longitudinal movement between vanes 22 and the water causes the vanes and sleeve 20 to be rotated in a clockwise direction, as viewed from above. This in turn causes the latch members 18 to move out of engagement with the brackets 18 on the cradles and hence the cradles and the bombs are now free to pivot about the pins 15.

When the vanes 35 on the lower ends of the bombs strike the water, the water pressure tends to pivot the bombs outwardly from the cradles and when the latches 18 are released from the brackets 18, both the bombs and the bomb cradles 70 are pivoted about pins 15.

In Fig. 5 there is illustrated the position of the rudder 26 with respect to the carrier before pivoting starts and in Fig. 6 these parts are shown after the pivoting has been completed. The rear 75 surface of the rudder 26 is curved and acts as a

cam against the enlarged portion 12 of the carrier to force the bomb away from the carrier as it pivots. The vanes 28 do not pivot with respect to the carrier, as is shown by comparing Figs. 5 and 6, but they do pivot with respect to the rudder 26 of the bomb and finally come to the position shown in Fig. 6, where they are parallel to the slot 27. Consequently, the pins 15 are released from the slot and the bomb may move in the direction illustrated by the arrow in Fig. 6 10 away from the carrier. Longitudinal movement of the bombs with respect to the cradles is not prevented by spring-pressed detents 31, due to the inclined surface of the upper ends of slots 32 which forces the detents into their sockets. Such 15 movement of the bombs is caused by the rotation of propeller 45, the power plant driving the propeller having been started due to the fact that lever 46 strikes the end of vane 28 as the bomb pivots with respect to such vane and with respect 20 to the carrier. The rotation of propellers 45 drive the several bombs in directions radiating from the point of impact. The vanes on the forward ends of the bombs serve as aquaplanes to prevent sinking of the bomb, while the rudders 26 25 hold the bombs on straight courses. If one or more of the bombs, while travelling through the water, strikes a target, the impact with the detonator head 36 causes explosion of the bomb.

Should a direct hit be scored and the device 30 land on a solid object, such as a ship, the members 37 are forced upwardly against the force of spring 42 and strike the detonator heads thereby immediately exploding all of the bombs.

While I have shown one more or less specific 35 embodiment of my invention, this has been done for purposes of illustration only and is not to be considered as limiting the scope of my invention which is to be determined by the appended claims viewed in the light of the prior art.

What I claim is:

1. In a bomb device adapted to be dropped from an aircraft, a bomb carrier, a bomb releasably secured thereto in vertical position, a detonator head at the lower end of said bomb, a member 45 movably secured to said carrier and extending below said head to protect said head from direct contact with the object on which the bomb device falls, and means for resisting movement of said member with respect to said carrier toward said head, the strength of the resisting means being such as to prevent substantial movement of said member when the device strikes water and to permit movement of said member into contact with said head when the device strikes a 50 solid object.

2. In a bomb device adapted to be dropped from an aircraft, a bomb carrier, a bomb releasably secured thereto in vertical position, a detonator head at the lower end of said bomb, a member 60 movably secured to said carrier and extending below said head to protect said head from direct contact with the object on which the bomb device falls, the lower surface of said member being streamlined for movement through water, and 65 means for resisting movement of said member with respect to said carrier toward said head, the strength of the resisting means being such as to prevent substantial movement of said member when the device strikes water and to permit movement of said member into contact with said head when the device strikes a 70 solid object.

3. In a bomb device adapted to be dropped from an aircraft into water, a bomb carrier, a plurality of bombs carried thereby, means for re- 75

- leasably securing said bombs to said carrier including a member rotatably secured to said carrier, and means for rotating said member upon impact with water to release said bombs.
- 5 4. In a bomb device adapted to be dropped from an aircraft into water, a bomb carrier including a central shaft, a plurality of bombs arranged around said shaft, a sleeve rotatably mounted on said shaft, means carried by said 5 sleeve for releasably securing said bombs to said carrier, said means being releasable by rotation of said sleeve, and spiral vanes on said sleeve for causing rotation of the sleeve upon impact with water.
- 10 5. In a bomb device adapted to be dropped from an aircraft into water, a bomb carrier including a central shaft, a plurality of bombs arranged around said shaft in substantially vertical position, a detonator head at the lower end 10 of each bomb, a sleeve rotatably mounted on said shaft, means carried by said sleeve for releasably securing said bombs to said carrier, said means being releasable by rotation of said sleeve, spiral vanes on said sleeve for causing rotation of the 15 sleeve upon impact with water, and arms carried by said shaft and extending to below said detonator heads to protect said heads from direct impact with the water.
- 20 6. In a bomb device adapted to be dropped from an aircraft into water, a bomb carrier including a central shaft, a plurality of bombs arranged around said shaft, a sleeve rotatably mounted on said shaft, means carried by said 20 sleeve for releasably securing said bombs to said carrier, said means being releasable by rotation of said sleeve, means for yieldably resisting rotation of said sleeve, and spiral vanes on said sleeve for causing rotation of said sleeve against the resistance of the last mentioned means upon 25 impact with water.
- 25 7. In a bomb device adapted to be dropped from an aircraft into water, a carrier, a plurality of bomb cradles pivotally secured to said carrier, a bomb releasably connected to each cradle, releasable means for preventing pivotal movement 30 of said cradles with respect to said carrier, means operative upon impact with water for releasing the first mentioned means, and means for pivoting said bombs and cradles upon impact with water, the connection between said bombs and cradles being arranged to be released upon pivoting thereof.
- 30 8. In a bomb device adapted to be dropped from an aircraft into water, a carrier, a plurality of bomb cradles pivotally secured to said carrier, a bomb releasably connected to each cradle and to said carrier, releasable means for preventing pivotal movement of said cradles and bombs with respect to said carrier, means operative upon impact with water for releasing the first mentioned means, means for pivoting said bombs and cradles upon impact with water, the connections of said bombs with said cradles and said carrier being arranged to be released upon pivoting of the bombs and cradles.
- 35 9. In a bomb device adapted to be dropped from an aircraft into water, a carrier, a plurality of bomb cradles pivotally secured to said carrier, releasable means for preventing pivotal movement of said cradles with respect to said carrier, a plurality of bombs, a pin and slot connection for preventing lateral movement between each bomb and the cradle therefor, means for pivotally connecting each bomb with said carrier; 40 means operative upon impact with water for
- releasing the first mentioned means, and means for pivoting said bombs and cradles upon impact with water, the pivotal connections between the bombs and carrier being releasable upon pivoting of the bombs to permit longitudinal movement of the bombs with respect to the cradles.
- 45 10. In a bomb device adapted to be dropped from an aircraft into water, a carrier, a plurality of bomb cradles pivotally secured to said carrier, releasable means for preventing pivotal movement of said cradles with respect to said carrier, a plurality of bombs, a pin and slot connection for preventing lateral movement between each bomb and the cradle therefor, means for pivotally connecting each bomb with said carrier, comprising a first pin secured to said carrier and extending through a longitudinal open ended slot in the bomb, a second pin secured to said carrier and spaced from said first pin, a vane pivoted to the bomb and arranged to extend at right angles to said slot and between said pins with said first pin between said vane and the closed end of said slot, means operative upon impact with water for releasing the first mentioned means, and means for pivoting said bombs and cradles upon impact with water, whereby said slot is turned to a position parallel with said vane and said first pin is released from said slot.
- 50 11. In a bomb device adapted to be dropped from an aircraft into water, a carrier, a plurality of bomb cradles pivotally secured to said carrier, releasable means for preventing pivotal movement of said cradles with respect to said carrier, a plurality of bombs, a pin and slot connection for preventing lateral movement between each bomb and the cradle therefor, means for pivotally connecting each bomb with said carrier comprising a first pin secured to said carrier and extending through a longitudinal open ended slot in the bomb, a second pin secured to said carrier and spaced from said first pin, a vane pivoted to the bomb and arranged to extend at right angles to said slot and between said pins with said first pin between said vane and the closed end of said slot, means operative upon impact with water for releasing the first mentioned means, means for pivoting said bombs and cradles upon impact with water, whereby said slot is turned to a position parallel with said vane and said first pin is released from said slot, a power plant in each bomb, and means for initiating operation of said power plant upon relative rotation of the bomb with respect to the vane.
- 55 12. In a bomb device adapted to be launched from an aircraft at a water-borne target, a bomb carrier, a bomb releasably secured thereto in substantially vertical position, a detonator head at the lower end of said bomb, and means secured to said carrier for preventing detonation upon impact with water and for causing detonation upon impact with the target.
- 60 13. In a bomb device adapted to be launched from an aircraft at a water-borne target, a bomb carrier, a bomb releasably secured thereto in substantially vertical position, a detonator head at the lower end of said bomb, means secured to said carrier for preventing detonation upon impact with water and for causing detonation upon impact with the target, and means for releasing said bomb from said carrier and turning the bomb through approximately 90° upon impact with water.
